REAGENT FEEDER

Louis D. Mills, Palo Alto, Calif., assignor to The Merrill Company, San Francisco, Calif., a corporation of California

Application February 6, 1939, Serial No. 254,865

7 Claims. (Cl. 221—125)

This invention relates generally to apparatus for feeding measured quantities of divided material. More particularly the invention relates to apparatus useful in certain chemical processes, such as cyanide systems for the precipitation of precious metals from cyanide solution, where it is desired to feed measured quantities of a metallic precipitant like zinc dust at a controlled rate.

It is an object of the invention to provide apparatus of the above character which will be simple in mechanical design, and which will operate satisfactorily with metallic dust of extremely fine particle fineness.

Another object of the invention is to provide an apparatus of the above character which can be readily charged with a predetermined quantity of metallic dust, and which will discharge or feed the metallic dust with a high degree of accuracy and reliability.

Further objects of the invention will appear from the following description in which the preferred embodiment of the invention has been set forth in detail in conjunction with the accompanying drawings.

Referring to the drawings:

Fig. 1 is a plan view taken along the line 1—1 of Fig. 2, and showing apparatus incorporating the present invention, in conjunction with the zinc emulsion cone of cyanidation equipment.

Fig. 2 is a cross-sectional view taken along the line 2—2 of Fig. 1.

Fig. 3 is a cross-sectional view taken along the line 3—3 of Fig. 2.

The apparatus illustrated in the drawings makes use of a suitable supporting framework 10, which serves to carry the various working parts. Suitable members of this frame carry journals 11, for the vertical rotatable shaft 12. The circularly contoured disc 13 is mounted upon the upper end of shaft 12, and is formed of a suitable material such as stainless steel or a like non-corrodible metal. The annular peripheral portion 14 of the disc 13 is cupped upwardly as illustrated in Fig. 2, thus forming a shallow annular trough for receiving a charge of the metallic dust.

In order to drive shaft 12 and disc 13 at a constant rate, there is a suitable drive connection to an electric motor 16 or like source of power. In this instance motor 16 carries a gear reduction box 17, and the drive pulley 18 from this gear box is connected to pulley 19 by belt 21. Pulley 19 is secured to the laterally extending shaft 22, which in turn carries a worm 23 for engaging the worm gear 24. Gear 24 is carried by the additional shaft 26, which in turn carries a worm 27 for engagement with worm gear 28. Gear 28 is mounted upon the lower portion of shaft 12. With such an arrangement

shaft 12 is driven at a relatively slow but constant rate, which may be varied in accordance with requirements. In a typical instance where zinc dust is being fed into a zinc emulsion cone, for precipitating cyanide solution, the shaft 12 may make one revolution for one operating shaft of say 8 hours.

In conjunction with the disc 13, means is employed for periodically displacing portions of a charge of material placed upon the disc 13. In this instance the displacing means is in the form of a wiper arm 31, which is secured to the horizontal shaft 32. The free end of arm 31 is provided with a projecting end portion 33 of flexible material, such as resilient rubber. As the arm 31 rotates its end portion 33 contacts and wipes across the upper surface of the curved disc portion 13, whereby any material in its path of movement is displaced over the outer lip of the disc. It will be noted from the cross-section illustrated in Fig. 2 that the curvation of portion 14 corresponds to the segment of a circle having as its center, the axis of shaft 32. Also shaft 32 is disposed so that the plane of rotation of arm 31 is generally vertical and coincident with the axis of shaft 12.

The shaft 32 is also provided with a suitable drive connection to the electric motor 16. Thus a pulley 34 is shown mounted upon one end of shaft 32, and this pulley is connected by a belt 36 to a pulley 37 on shaft 22. The speed of rotation of shaft 32 is made consistent with the speed of rotation of disc 13. Thus where the disc 13 rotates one revolution in 8 hours, the shaft 32 and wiper 31 may rotate at a speed of about 2½ revolutions per minute.

It is desirable to provide a cover for disc 13 in order to protect the charge of metallic dust from wind and moisture. The protecting cover 38 in this instance is made of suitable sheet metal, and its side edges 41 are engaged in guide tracks 42. The forward portion of the cover is provided with a slot 43, for accommodating the wiper arm 31. When it is desired to apply a charge of dust upon the disc 13, this cover can be slid back to an out-of-the-way position, after which it is returned to its normal position overlying the disc.

As previously mentioned the apparatus described above can be utilized to advantage in connection with cyanidation equipment. Thus the drawings illustrate a zinc emulsion cone 46, the lower end of which connects with a flow pipe 47 through which cyanide solution is conveyed. Extending upwardly through the cone 46, there is a rod 48, the upper end of which is loosely retained by the guide or journal 49. Rod 48 is periodically reciprocated by a rotating cam 51, in conjunction with a tappet or collar 52 mounted upon rod 48. Cam 51 can be driven from the

same source of power as is used for the reagent feeder, namely the motor 16. Thus it is shown mounted upon the horizontal shaft 53, one end of which carries a pulley 54. Pulley 54 is connected by belt 56, to the pulley 57 on shaft 32.

The lower end of rod 48 carries a valve member 59, which cooperates with the valve seat 61. At periodic intervals cam 51 elevates the tappet 52 and rod 48, to permit a mixture of dust and solution to pass down to intermix with solution flowing through pipe 47. In cyanidation systems it is customary for barren cyanide solution to be supplied to the cone 46, where it intermixes with the zinc dust.

In operating the apparatus described above a measured quantity of the divided material is placed upon the disc 13, and is distributed by the operator over the concave portion 14. Fig. 2 illustrates such a charge of material after it is supplied to the disc. Where the apparatus is being used with cyanidation equipment as previously described, sufficient finely divided zinc dust is employed for a given shift, as for example an 8 hour period. Upon starting the motor 16 the disc 13 is slowly rotated while the wiper arm 31 periodically moves across the upper concave surface of the portion 14. Each time the arm 31 wipes across the disc, a portion of the charge is displaced over the outer lip of the disc. Because of the arrangement of parts illustrated in the drawings, the discharged portion of the material drops into the zinc emulsion cone 46, for mixture with the barren cyanide solution. The apparatus continues to function in the manner described until the disc 13 has made one complete revolution, or has rotated sufficiently far to cause displacement of the entire charge of material. One now stops the motor 15, and after the protecting cover 38 has been moved to an out-of-the-way position, a new measured charge of material can be applied to the disc.

One characteristic of the present apparatus is that it will give accurate results with metallic dust of extremely fine particle fineness. Such material is difficult to feed at a controlled rate, due to the fact that it does not tend to assume a distinct angle of repose. With the present apparatus finely divided zinc dust can be fed at a relatively constant rate, and without any spill or wastage of the material. It is also characteristic of my apparatus that it can be readily charged by an operator. It is a simple matter for the operator to apply a measured charge to the disc 13, because of the concave form of the peripheral portion 14.

I claim:

1. In a machine for feeding measured quantities of a divided material like metallic dust, means forming a concave surface for supporting a measured quantity of the material, a movable wiper adapted to contact and wipe across said concave surface, means for moving said surface at a constant rate relative to said wiper means, and drive means for said wiper serving to cause said wiper to periodically wipe over said surface to displace portions of the material from said surface.

2. In a machine for feeding measured quantities of a divided material like metallic dust, means forming an annular surface for supporting a measured quantity of the material, said surface being mounted for rotation about a ver-

tical axis, the surface being concavely curved to retain the charge of material, means for rotating said supporting surface at a constant rate, a wiper arm mounted for rotation about a horizontal axis located above said surface, the free end of said wiper arm being adapted to contact and wipe across said surface, and means for rotating said wiper arm at a constant rate.

3. In a machine for feeding measured quantities of a material like metallic dust, means forming a surface for supporting a quantity of the material, a movable wiper adapted to contact and wipe across said surface, means for moving said surface at a constant rate relative to said wiper, and drive means for said wiper serving to cause the wiper to periodically wipe over said surface in a direction substantially normal to the direction of movement of the material into the region of operation of the wiper.

4. In a machine for feeding measured quantities of a material like metallic dust, means forming a surface for supporting a quantity of the material, means for moving said surface at a constant rate, a wiper arm mounted for rotation about a generally horizontal axis located above said surface, the free end of said wiper arm being adapted to contact and wipe across said surface, and means for rotating said wiper arm at a constant rate, the surface being arranged to advance the material to the region of operation of the wiper in a direction normal to the plane of rotation of the wiper.

5. In a machine for feeding measured quantities of a material like metallic dust, means forming an annular surface for supporting a quantity of the material, said surface being mounted for rotation about a generally vertical axis, means for rotating said supporting surface at a constant rate, a wiper arm mounted for rotation about a generally horizontal axis located above said surface, the free end of said wiper arm being adapted to contact and wipe across said surface, and means for rotating said wiper arm at a constant rate.

6. In a machine for accurately feeding quantities of a finely divided material like metallic zinc dust, means forming a concave annular surface for supporting a measured quantity of the material, a wiper arm, means serving to mount the wiper arm for rotation in a plane generally perpendicular to the concave annular surface, the free end of the wiper describing a circle having a radius corresponding generally to that of the concave surface, and means for continuously advancing said surface toward the wiper to cause displacement of portions of the material from the same.

7. In a machine for accurately feeding quantities of a finely divided material like metallic zinc dust, means forming a concave annular surface for supporting a measured quantity of the material, a flexible wiper arm, means serving to mount the flexible wiper arm for rotation in a plane generally perpendicular to the concave annular surface, the free end of the flexible wiper describing a circle having a radius corresponding generally to that of the concave surface, and means for continuously advancing said surface toward the flexible wiper to cause displacement of portions of the material from the same.

LOUIS D. MILLS.
